UNITED STATES PATENT OFFICE

2,038,953

LEAD PENCIL

Clarence F. Norlin, Chicago, Ill.

Application November 15, 1934, Serial No. 753,174

19 Claims. (Cl. 120—14)

The present invention relates more particularly to lead pencils of the so-called magazine type, wherein leads to be successively used in the pencil are stored and removed from said magazine when needed for use, the present invention being an improvement on that disclosed in my prior Patent No. 1,937,779, granted me on December 5, 1933.

The primary object of the present invention is to provide a simple and efficient magazine arrangement for such lead pencils, which is capable of economical production and highly efficient in use.

Other objects will appear hereinafter.

The invention consists in the combinations and arrangements of parts hereinafter described and claimed.

The invention will be best understood by reference to the accompanying drawings forming a part of the specification and in which:

Fig. 1 is an enlarged sectional view taken through the tip end of a magazine pencil showing a magazine arrangement embodying the invention.

Fig. 2 is a section taken substantially on line 2—2 of Fig. 1.

Fig. 3 is a section taken substantially on line 3—3 of Fig. 1.

Fig. 4 is a perspective view of a magazine frame employed in the construction and shown removed from the pencil barrel.

Fig. 5 is a perspective view on a small scale of the complete pencil.

Fig. 6 is a view similar to Fig. 1, but showing a modified magazine arrangement.

Fig. 7 is a section taken substantially on lines 7—7 of Fig. 6.

Fig. 8 is a section similar to Fig. 7 but showing the magazine in a different position; and

Fig. 9 is a perspective view of the magazine removed from the pencil barrel.

The embodiment of the invention illustrated in Figs. 1, 2, 3, 4 and 5, comprises a pencil barrel 10 having a pencil tip 11 provided with a lead bore 12 in registration with a reciprocating plunger 13. The plunger 13 is carried by an operating head 14 equipped with an eraser 15, best shown in Fig. 5. These parts of the pencil are identically the same as those disclosed in my said prior Patent No. 1,937,779, and require no further description here.

The barrel 10 is provided with a laterally opening magazine recess 16 adjacent the tip 11, adapted and arranged to receive removably the inner

end of a magazine frame 17. For this purpose the frame 17 is equipped with spring balls 18, arranged to engage notches 19, as best shown in Fig. 2. Notches 20 are provided as shown to facilitate removal of the frame 17 from the barrel, 5 as will be readily understood.

A cylindrical magazine 21 is rotatably mounted as indicated in the magazine frame 17, and is provided with a central bore or recess 22 having a torsional spring 23 arranged therein as shown. 10 One end 24 of the spring 23 is attached, as shown, to the magazine 21, the other end 25 of said spring being attached as shown to the end of the magazine frame 17. The magazine 21 is provided with six lead pockets 26 arranged circumferentially 15 as shown so as to be brought successively into registration with the tip bore 12 and the plunger 13, the end of the frame 17 being provided with a central bore 27 to permit of reciprocations of the plunger 13 through the pockets 26, and the 20 bore 12, as will be readily understood.

By this arrangement it is to be noted that the plunger 13 may be readily manipulated to pass through the pockets 26, and into the bore 12 when desired. 25

The magazine 21 is provided with 3 peripheral slots 28, and a stop plate 29 is secured as shown to the inner face of the frame 17, and is provided with 3 stop fingers 30 projecting into the slots 28, in positions to traverse the pockets 26 when the magazine 21 revolves. A sight opening 31 is provided in the outer wall of the frame 17 and corresponding numbers are placed on the periphery of the magazine 21 to indicate which of the magazine pockets is in registration with the lead bore 30 12.

In use and in operation leads 32 are placed in the pockets 26, the magazine 21 being rotated as it is being filled, to place the torsional spring 23 under tension, each lead 32 being inserted behind the stops 30 to prevent reverse rotation of said magazine, as will be readily understood. Then the magazine frame 17 is inserted in the recess 16 and the pencil is ready for use. By depression 40 of the plunger 13 the lead 32 aligned therewith is forced into the tip bore 12 and is utilized for writing until consumed, and as is more fully explained in my said Patent No. 1,937,779. When said lead has been consumed the plunger 13 is retracted. As soon as said plunger 13 is removed 45 from the corresponding pocket 26, the spring 23 serves to step up the magazine 21 until the next successive lead encounters the stops 30, whereby said next lead is placed in registration with the lead bore 12 for use as above explained. 50

Thus each lead in the magazine pockets 26 may be successively brought into registration with the tip bore 12 and utilized in the pencil without refilling the magazine. By this arrangement a simple and effective magazine arrangement is provided for the pencil, which is capable of economical production and is highly efficient in use. In this connection it is also to be noted that the magazine arrangement is such as to be fully operable, notwithstanding the accidental breakage of any of the leads 32.

In the modification illustrated in Figs. 6, 7, 8 and 9, a different magazine arrangement has been disclosed. In this arrangement the magazine recess 16' is rectangular in form to receive a rectangular magazine frame 33 having stop flanges 34 at its ends, there being notches 35 in the pencil barrel to facilitate removals of the magazine frame. The magazine frame 33 is made of a size 20 to snugly fit and to be frictionally held in the recess 16'.

Arranged in the magazine frame 33 is a laterally shiftable rectangular magazine 36 having 3 lead pockets 37 therein, as shown. A leaf spring 38 is arranged in the frame 33 to force the magazine 36 normally inwardly to bring the pockets 37 successively into registration with the bore 12, and plunger 13. Stop lugs 39 are struck from the sides of the frame 33 to project into notches 40 intersecting the lead pockets 37.

In use the magazine 36 is forced into the frame 33 and the pockets 37 filled with leads, the outermost lead engaging the stops 39 to prevent return movement of the magazine. Then the magazine frame 33 is inserted in the recess 16' to bring the innermost lead 32 into registration with the tip bore 12 and plunger 13, when the leads may be utilized by manipulations of the plunger 13, as before. As each lead is utilized, the spring 38 forces the magazine 36 inwardly to bring another lead into registration with the tip bore and plunger until the supply in the magazine is exhausted. This arrangement also constitutes a simple and efficient arrangement for the purpose which is capable of somewhat more economical production than the one already described, but does not contain as many leads. Here again the arrangement is fully operative, notwithstanding the accidental breakage of one or more of the leads.

While I have illustrated and described the preferred constructions for carrying the invention into effect, these are capable of variation and modification without departing from the spirit of the invention. I, therefore, do not wish to be limited to the precise details described, but desire to avail myself of such variations and modifications as fall within the scope of the appended claims.

I claim:

1. A pencil barrel, a pencil tip having a lead bore, and a reciprocating plunger in alignment with and arranged to feed leads through said tip bore, in combination with a shiftable lead magazine, mounted in said barrel and provided with lead receiving pockets, arranged to register successively with said bore and plunger there being one or more slots in said magazine giving lateral access to said pockets; one or more stops projecting laterally into said slots to engage the leads or said plunger when in said pockets and hold the same in registration with said bore; and means for shifting said magazine to bring said pockets successively into registration with said bore and plunger.

2. A pencil barrel, a pencil tip having a lead bore, and a reciprocating plunger in alignment with and arranged to feed leads through said tip bore, in combination with a shiftable lead magazine removably mounted in said barrel and provided with lead receiving pockets arranged to register successively with said bore and plunger; and means for shifting said magazine to bring said pockets successively into registration with said bore and plunger. 5

3. A pencil barrel, a pencil tip having a lead bore, and a reciprocating plunger in alignment with and arranged to feed leads through said tip bore, in combination with a shiftable lead magazine, mounted in said barrel and provided with 15 lead receiving pockets, arranged to register successively with said bore and plunger, there being one or more slots in said magazine giving lateral access to said pockets; one or more stops projecting laterally into said slots to engage the leads or 20 said plunger when in said pockets and hold the same in registration with said bore; and means automatically controlled by reciprocations of said plunger for shifting said magazine to bring said pockets successively into registration with said 25 bore and plunger.

4. A pencil barrel, a pencil tip having a lead bore, and a reciprocating plunger in alignment with and arranged to feed leads through said tip bore, in combination with a shiftable lead magazine removably mounted in said barrel and provided with lead receiving pockets arranged to register successively with said bore and plunger; and means automatically controlled by reciprocations 30 of said plunger for shifting said magazine to bring 35 said pockets successively into registration with said bore and plunger.

5. A pencil barrel, a pencil tip having a lead bore, and a reciprocating plunger in alignment with and arranged to feed leads through said tip bore, in combination with a shiftable lead magazine, mounted in said barrel and provided with lead receiving pockets, arranged to register successively with said bore and plunger, there being one or more slots in said magazine giving lateral 45 access to said pockets; one or more stops projecting laterally into said slots to engage the leads or said plunger when in said pockets and hold the same in registration with said bore; and spring operable means for shifting said magazine to bring 50 said pockets successively into registration with said bore and plunger.

6. A pencil barrel, a pencil tip having a lead bore, and a reciprocating plunger in alignment with and arranged to feed leads through said tip bore, in combination with a shiftable lead magazine removably mounted in said barrel and provided with lead receiving pockets arranged to register successively with said bore and plunger; and spring operable means for shifting said magazine 60 to bring said pockets successively into registration with said bore and plunger.

7. A pencil barrel, a pencil tip having a lead bore, and a reciprocating plunger in alignment with and arranged to feed leads through said tip bore, in combination with a shiftable lead magazine, mounted in said barrel and provided with lead receiving pockets, arranged to register successively with said bore and plunger, there being one or more slots in said magazine giving lateral 70 access to said pockets; one or more stops projecting laterally into said slots to engage the leads or said plunger when in said pockets and hold the same in registration with said bore; and spring operable means automatically controlled by re- 75

ciprocations of said plunger for shifting said magazine to bring said pockets successively into registration with said bore and plunger.

8. A pencil barrel, a pencil tip having a lead bore, and a reciprocating plunger in alignment with and arranged to feed leads through said tip bore, in combination with a shiftable lead magazine removably mounted in said barrel and provided with lead receiving pockets arranged to register successively with said bore and plunger; and spring operable means automatically controlled by reciprocations of said plunger for shifting said magazine to bring said pockets successively into registration with said bore and plunger.

15. 9. A pencil barrel having a recess in one side thereof, a pencil tip having a lead bore, and a reciprocating plunger in alignment with and arranged to feed leads through said tip bore, in combination with a magazine frame removably inserted in said recess; a shiftable lead magazine mounted on said frame and provided with lead receiving pockets arranged to register successively with said bore and plunger; and means for shifting said magazine to bring said pockets successively into registration with said bore and plunger.

30. 10. A pencil barrel having a recess in one side thereof, a pencil tip having a lead bore, and a reciprocating plunger in alignment with and arranged to feed leads through said tip bore, in combination with a magazine frame removably inserted in said recess; a shiftable lead magazine mounted on said frame and provided with lead receiving pockets arranged to register successively with said bore and plunger; and means automatically controlled by reciprocations of said plunger for shifting said magazine to bring said pockets successively into registration with said bore and plunger.

35. 40. 11. A pencil barrel having a recess in one side thereof, a pencil tip having a lead bore, and reciprocating plunger in alignment with and arranged to feed leads through said tip bore, in combination with a magazine frame removably inserted in said recess; a shiftable lead magazine mounted on said frame and provided with lead receiving pockets arranged to register successively with said bore and plunger; and spring operable means for shifting said magazine to bring said pockets successively into registration with said bore and plunger.

45. 50. 55. 12. A pencil barrel having a recess in one side thereof, a pencil tip having a lead bore, and a reciprocating plunger in alignment with and arranged to feed leads through said tip bore, in combination with a magazine frame removably inserted in said recess; a shiftable lead magazine mounted on said frame and provided with lead receiving pockets arranged to register successively with said bore and plunger; and spring operable means automatically controlled by reciprocations of said plunger for shifting said magazine to bring said pockets successively into registration with said bore and plunger.

60. 65. 70. 75. 13. A pencil barrel having a recess in one side thereof, a pencil tip having a lead bore and a reciprocating plunger in alignment with and arranged to feed leads through said tip bore, in combination with a magazine frame removably inserted in said recess; a shiftable lead magazine mounted on said frame and provided with lead receiving pockets arranged to register successively with said bore and plunger, there being one or more slots in said magazine giving lateral access

to said pockets; a spring normally forcing movement of said magazine to bring said pockets successively into such registration; and one or more stops projecting laterally into said slots to engage the leads or said plunger when in said pockets to stop said magazine with the successive pockets in registration with said bore and plunger.

14. A pencil barrel having a recess in one side thereof, a pencil tip having a lead bore and reciprocating plunger in alignment with and arranged to feed leads through said tip bore, in combination with magazine frame removably inserted in said recess; a rotatable lead magazine mounted on said frame and provided with lead receiving pockets arranged to register successively with said bore and plunger, there being one or more slots in said magazine giving laterally access to said pockets; a spring normally forcing movement of said magazine to bring said pockets successively into such registration; and one or more stops projecting laterally into said slots to engage the leads or said plunger when in said pockets to stop said magazine with the successive pockets in registration with said bore and plunger.

15. A pencil barrel having a recess in one side thereof, a pencil tip having a lead bore and reciprocating plunger in alignment with and arranged to feed leads through said tip bore, in combination with magazine frame removably inserted in said recess; a laterally sliding magazine mounted on said frame and provided with lead receiving pockets arranged to register successively with said bore and plunger, there being one or more slots in said magazine giving laterally access to said pockets; a spring normally forcing movement of said magazine to bring said pockets successively into such registration; and one or more stops projecting laterally into said slots to engage the leads or said plunger when in said pockets to stop said magazine with the successive pockets in registration with said bore and plunger.

16. A pencil barrel, a pencil tip having a lead bore, and a reciprocating plunger in alignment with and arranged to feed leads through said bore, in combination with a rotatable lead magazine mounted in said barrel and provided with lead receiving pockets arranged to register successively with said bore and plunger, there being one or more slots in said magazine giving lateral access to said pockets; one or more stops projecting laterally into said slots to engage the leads or said plunger when in said pockets and hold the same in registration with said bore; and spring operable means automatically controlled by reciprocations of said plunger for shifting magazine to bring said pockets successively into registration with said bore and plunger.

17. A pencil barrel, a pencil tip having a lead bore, and a reciprocating plunger in alignment with and arranged to feed leads through said bore, in combination with a laterally sliding magazine mounted in said barrel and provided with lead receiving pockets arranged to register successively with said bore and plunger; and spring operable means automatically controlled by reciprocations of said plunger for shifting magazine to bring said pockets successively into registration with said bore and plunger.

18. A pencil barrel, a pencil tip having a lead bore, and a reciprocating plunger in alignment with and arranged to feed leads through said tip bore, in combination with a spring actuated shiftable lead magazine mounted in said barrel and

provided with lead receiving pockets arranged to register successively with said bore and plunger; and a stop arranged to engage the leads or said plunger when in said pockets and hold the same in registration with said bore.

5. 19. A pencil barrel, a pencil tip having a lead bore, and a reciprocating plunger in alignment with and arranged to feed leads through said tip

bore, in combination with a spring actuated rotatable lead magazine mounted in said barrel and provided with lead receiving pockets arranged to register successively with said bore and plunger; and a stop arranged to engage the leads or said plunger when in said pockets and hold the same in registration with said bore.

CLARENCE F. NORLIN.
